US0D1038040S

(12) **United States Design Patent** (10) **Patent No.:** **US D1,038,040 S**
(45) **Date of Patent:** **** Aug. 6, 2024**

(54) **ELECTRICAL BOX**

(71) Applicant: **Shenzhen JinDouZi Trading Co., Ltd,**
Guangdong (CN)

(72) Inventor: **Minshan Hong**, Guangdong (CN)

(**) Term: **15 Years**

(21) Appl. No.: **29/908,992**

(22) Filed: **Jan. 16, 2024**

(51) **LOC (14) Cl.** **13-03**

(52) **U.S. Cl.**
USPC **D13/152**

(58) **Field of Classification Search**

USPC D13/152, 199, 162.1, 178, 184, 139.8;
D1/100

CPC .. H01R 13/6658; H01R 9/24; H01R 13/5227;
H02G 3/14; H02G 15/117

See application file for complete search history.

(57) **CLAIM**

The ornamental design for an electrical box, as shown and
described.

DESCRIPTION

FIG. 1 is a perspective view of the electrical box showing
my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partially enlarged view taken from FIG. 1.

In the drawings, the broken lines are for the purpose of
illustrating portions of the electrical box that form no part of
the claimed design.

1 Claim, 9 Drawing Sheets
